(57) **CLAIM**

The ornamental design for a power steering pump bracket, as shown and described.

DESCRIPTION

FIG. 1 is a first perspective view of a first design of a power steering pump bracket;

FIG. 2 is a second perspective of the design of FIG. 1;

FIG. 3 is a top view of the design of FIG. 1;

FIG. 4 is a bottom view of the design of FIG. 1;

FIG. 5 is a left side view of the design of FIG. 1;

FIG. 6 is a right side of the design of FIG. 1;

FIG. 7 is a front view of the design of FIG. 1;

FIG. 8 is a rear view of the design of FIG. 1;

FIG. 9 is a first perspective view of a second design of a power steering pump bracket;

FIG. 10 is a second perspective of the design of FIG. 9;

FIG. 11 is a top view of the design of FIG. 9;

FIG. 12 is a bottom view of the design of FIG. 9;

FIG. 13 is a left side view of the design of FIG. 9;

FIG. 14 is a right side of the design of FIG. 9;

FIG. 15 is a front view of the design of FIG. 9; and,

FIG. 16 is a rear view of the design of FIG. 9.

In the drawings, the broken lines depict unclaimed portions of the power steering pump bracket only and form no part of the claimed design.
